UNITED STATES PATENT OFFICE.

GERD HOBBISIEFKEN, OF BURLINGTON, IOWA.

DEVICE FOR FACILITATING THE FITTING AND HANGING OF DOORS.

Application filed April 14, 1926. Serial No. 102,012.

Figure 1 is a face view of the invention as applied to a doorway.

Figure 2 is a similar view of the invention alone.

5 Figure 3 is a perspective view of a portion of the invention.

The invention has relation to a device for fitting and hanging doors, an object being to provide a device for this purpose designed 10 to facilitate the hanging of the door and to save time and labor. Other objects and advantages will appear hereinafter.

The invention consists in the novel construction and combinations of parts as set 15 forth in the appended claims.

In the accompanying drawings illustrating the invention the numeral 1 designates a skeleton like rectangular form, designed to fit into the doorway or opening adjacent the 20 jamb thereof, the side bars 2 of said form being adjustable for length by means of joint plates 3 engaging said side bars and extending above and below the adjacent ends of said bars, suitable adjusting means being 25 provided such as a series of perforations of said side bars adapted to align with a series of perforations 6 of said joint plates, and transverse bolts 7 engaging the aligned perforations of side bars and joint plates. The 30 joint plates are provided with stiffening flanges 8 upon the inner edges thereof.

The upper and lower bars of the form are also made adjustable for length, preferably by means of lapping sections 9, 9, usually of flat or strap metal as are also said joint plates, and provided with series of aligned perforations 10, engaged by transverse bolts 11. The side bars 2 are preferably of wood, the entire form being of light 40 skeleton form, adapted to be readily transported from place to place.

The skeleton form 1 is provided with upper and lower rigid transverse abutment and brace bars 12, 12, respectively, each of unitary light channel form, and extending the full breadth of the rectangular form 1 and at the ends beyond the side bars of said form, and provided at each end with a series of perforations 13, adapted respectively to align 45 with a perforation 14 of the side bar, the aligned perforations being engaged by a transverse bolt 15, said abutment bars in the application of the form 1 to the doorway 50

or opening fitting against the door casing 55 at one side thereof and holding the form 1 precisely vertical in said doorway.

The sections 9, 9, of the upper and lower bars of the form 1, are more or less bendable or flexible owing to being made of light 60 strap metal and the upper and lower rigid brace or stiffening and abutment bars 12, 12, correct this and make the form 1 rigid as a whole.

Doorways do not usually precisely fit 65 doors, the door of nearest stock size being usually ordered and trimmed down to make a correct fit. Frequently two men are required one for the purpose of holding the door in position within the doorway, and the 70 other to mark the places where the door needs trimming. The door being trimmed to fit, one man commonly holds it again within the doorway, and another man marks the places for the locks and hinges, and when finally 75 the door is hung, it is frequently taken down again for trimming the bottom thereof so that it will be the proper distance from the floor.

In the present case, the device or form is 80 adjustable to precisely fit the doorway, the series of perforations having the members thereof sufficiently close together for this purpose, and the form being properly adjusted, it is only necessary to place it upon the door, which may then be readily marked 85 for trimming, all by one man.

I claim:

1. A device to facilitate the fitting and hanging of doors, comprising a skeleton like rectangular form of light portable nature 90 and having rigid side frame bars and upper and lower flexible frame bars adjustable for length to precisely fit the doorway, and upper and lower rigid unitary abutment and stiffening bars carried by and having adjustable bolt connection with said side bars and extending each the full breadth of said form and beyond the same at the ends, said abutment and stiffening bars having plane inner faces located in the same plane as the 95 outer faces of said side bars.

2. A device to facilitate the fitting and hanging of doors, comprising a skeleton like rectangular form of light portable nature and having side frame bars of wood and 100 upper and lower frame bars of light bendable strap metal, said side bars being sec- 105

tional and provided with light strap metal joint plates having inner stiffening flanges, and said upper and lower frame barslapping each other and being adjustable for length as are also said side bars, and upper and lower rigid unitary abutment and stiffening bars carried by and having adjustable

bolt connection with said side bars and extending each the full breadth of said form and beyond the same at the ends, and having plane inner faces located in the same plane as the outer faces of said side bars. 10

In testimony whereof I affix my signature.
GERD HOBBISIEFKEN.
